FREDERICK E. LAMB AND ONE-THIRD TO FRANK A. CAMPBELL, BOTH OF
ST. LOUIS, MISSOURI.

WASHING-MACHINE.

1,379,247.

Specification of Letters Patent. Patented May 24, 1921.

Application filed October 11, 1920. Serial No. 416,124.

To all whom it may concern:

Be it known that I, SAMUEL D. CARPENTER, a citizen of the United States, residing at St. Louis, Missouri, have invented a certain new and useful Improvement in Washing-Machines, of which the following is a full, clear, and exact description, such as will enable others skilled in the art to which it appertains to make and use the same, reference being had to the accompanying drawings, forming part of this specification.

My invention relates generally to washing machines and more particularly to that type of washing machine in which the fabrics to be washed are placed in a clothes container which is agitated in a suitable compartment or tank.

The principal objects of my invention are, to provide a washing machine which is simple in operation and of durable construction, and which will efficiently and quickly wash and rinse the clothes without the necessity of transferring the same to various tanks or tubs.

25 A further object of my invention is to provide a washing machine having a movable clothes container adapted to agitate the clothes placed therein and provided with suitable connections whereby cleansing or rinsing fluid may be circulated through said container at the will of the operator.

Another object of my invention is to provide a washing machine having a plurality of compartments which are adapted to contain various cleansing and laundry solutions such as soap suds water, rinsing water, bluing water, and suitable connections for connecting said compartments with the washing tank containing the clothes to be washed.

40 A still further object of my invention is to provide a clothes container for washing machines adapted to be actuated so as to agitate the clothes placed therein and having suitable means disposed thereon and 45 connections for said means whereby streams of cleansing fluid are forcibly injected into said clothes container and upon the clothes placed therein.

With the foregoing and other objects in view, my invention consists in the novel features of construction and arrangement of parts, hereinafter more fully described and

claimed, and illustrated in the accompanying drawings, in which—

Figure 1 is a front elevation of my improved washing machine. 55

Fig. 2 is a rear elevation.

Fig. 3 is a vertical cross section taken on the line 3—3 of Fig. 2.

Fig. 4 is a horizontal cross section taken on the line 4—4 of Fig. 3 and partially broken away to more clearly illustrate the invention. 60

Fig. 5 is a vertical cross section taken on the line 5—5 of Fig. 3. 65

Fig. 6 is a cross section taken on the line 6—6 of Fig. 4.

Fig. 7 is a fragmentary cross section of the cylinder.

Fig. 8 is a longitudinal cross section taken on the line 8—8 of Fig. 4. 70

Fig. 9 is a perspective view of the end of the driving shaft.

Fig. 10 is a perspective view of the cylinder trunnion adapted to coöperate with the driving shaft. 75

Fig. 11 is a detail view of one of the valves utilized for controlling the connection between the washing compartment and the soap suds and clear water tanks. 80

Referring by numerals to the accompanying drawings, 10 represents the framework of the washing machine having side walls 11 and 12 and end walls 14 and 15. The chamber within these walls is divided by means of a vertical transverse wall 16 into two compartments 17 and 18. 17 is the washing tank or main compartment and is provided with bottom wall 19. 18 is the auxiliary tank and can be used either as a soaking tank or bluing tank and is provided with bottom wall 20. 85

The space under the washing tank is enclosed by bottom wall 21 and vertical end wall 22 to form a chamber which is divided by a vertical longitudinal wall 24 into two smaller tanks, one of which, 25, is arranged to contain clear or rinsing water, and the other is a soap suds tank 26. Under tank 18 and suitably supported on framework 10 is an electric motor 27. Pump 28 having an inlet pipe 29 and an outlet pipe 30 is adapted to be driven by motor 27 and is controlled by clutch 31. The inlet pipe 29 is 90

provided with branch pipes 32 and 33. Branch pipe 32 connects pump 28 with the soap suds tank 26 and is controlled by valve 34. Branch pipe 33 connects pump 28 with 5 clear water tank 25 and is controlled by manually operated valve 35. The outlet pipe 30 extends outwardly and upwardly of side wall 12 and terminates in the cylinder bearing 37 which is fixed to the inner side 10 of side wall 12.

A reduction gearing 38 located in housing 39 is geared to pinion 40 of motor 27 and drives shaft 41 which extends upwardly adjacent to side wall 11 and operates 15 wringer 42. Clutch 44 controls wringer 42 so that it can be disconnected from shaft 41. A shaft 45, also driven by gearing 38, extends upwardly and rearwardly and operates suitable cylinder reversing mechanism 20 46 supported on side wall 11. The reversing mechanism can be disconnected from shaft 45 and rendered inoperative by means of clutch 47. A short horizontal shaft 48 extends outwardly from the reversing mechanism 25 through side wall 11 into chamber 17 and its end is provided with a recess 48^a, non-circular in cross section.

The washing compartment 17 is provided with a cylinder 49 having a header 50 and 30 an end wall 51. The cylinder 49 is arranged for rotation in said compartment by means of a hollow trunnion 52 which is fixed to header 50 and adapted to operate in bearing 37 on side wall 12 and by means 35 of a trunnion 54 carried by end wall 51 and adapted to be seated in the recessed end of shaft 48. A locking plate 55 hinged to the recessed end of shaft 48 locks trunnion 54 in position on said shaft by means of a 40 butterfly nut 56. Cylinder 49 is made of foraminous material in order to readily drain the water.

Longitudinally disposed on the inner periphery of said cylinder are paddles or 45 stirrers 57 which are of hollow construction and communicate with chamber 50^a in the header 50. The walls of said paddles taper toward the axis of the cylinder and formed in the apex of each paddle are orifices 57^a. 50 The end of inlet pipe 30 enters bearing 37 and terminates within the hollow trunnion 52 so that connections are established between tanks 25 and 26 and paddles 57 by means of branch pipes 31 and 32 in pipe 55 29, pump 28 and outlet pipe 30 and which connections are controlled by means of manually operated valves 34 and 35.

By making hollow trunnion 52 conical and recessing the end of shaft 48, cylinder 60 49 can be removed from tank 17 by releasing locking plate 55, raising trunnion 54 out of recess 48^a in which it was seated, moving cylinder 49 toward side wall 11 until trunnion 52 is displaced from bearing 37 when 65 cylinder 49 can be lifted out of tank 17.

Cylinder 49 is provided with hinged doors 58 which are adapted to be locked in closed position. Bottom wall 19 of cylinder 10 is provided with valve 59 which controls the communication between said cylinder tank 70 and the soap suds tank and valve 60 which controls the communication between the cylinder tank and the clear water tank 25.

A section or bottom wall 19 is made removable as indicated at 61 to provide access to the soap suds tank and the clear water tank for the purpose of cleaning. A drain valve 64 permits the draining of soap suds tank and valve 65 permits the draining of the clear water tank. Tank 17 is 80 provided with a drain valve 66 and tank 18 is provided with drain valve 67.

In order to maintain the solution in the soap suds tank at the proper temperature, a suitable heating member 68 is located 85 directly below said tank and is controlled by valve 69.

In the operation of my improved washing machine, tank 25 is filled with clear water through valve 60 and tank 26 is filled through valve 59. The soap suds solution in tank 26 is heated by heating means 68 to the desired temperature at the same time partially heating water in tank 25 by virtue of the fact that portion of the heat is 95 imparted to water in tank 25 through wall 24. The soiled fabrics are placed in cylinder 49 through the door 58 which is then locked in its closed position. Valve 34 is opened while valve 35 remains closed and 100 valve 59 is opened and valve 60 closed.

Motor 27 is set in operation so that pump 28 is actuated whereby the heated soap suds solution is forced to circulate through branch pipe 31, controlling valve 34, inlet 105 connection 29, to pump 28, thence through outlet pipe 30 into the chamber 50^a in header 50 where the soap suds solution is distributed under pressure to the hollow paddles or stirrers 57 from which it issues in jets or 110 streams through apertures 57^a thoroughly spraying the fabrics or clothes placed in cylinder 49.

As the cylinder is made of foraminous material, the solution after passing through 115 the fabrics in cylinder 49 leaves the cylinder and returns through valve 59 into the tank 26 carrying with it the dirt and sediment which settles in the bottom of the tank. During this spraying operation, cylinder 120 49 is actuated first in one direction and then in the opposite by means of gearing 38, shaft 45, reversing mechanism 46, and shaft 47, so that the fabrics in the cylinder are constantly agitated through the action of 125 paddles 57 which pick up each piece of fabric, raise it out of the water for a short distance, and then drop it back again. This combined action of spraying and forcibly circulating the cleansing fluid through the 130

- clothes and of agitating the same thoroughly washes and cleanses the fabrics without injury. After the fabrics have been subjected to this spraying and agitating action 5 for the desired length of time, pump 28 is stopped by means of clutch 31 and valve 34 is closed. Preferably the cylinder 49 is operated for a short period of time after the circulation has ceased with the valve 10 59 opened in order to drive all the soap suds solution from the fabrics by the agitating action of the cylinder and to permit the solution to return into tank 26.

In the next operation, valves 35 and 60 15 are opened while valve 59 is closed. Pump 28 is set in operation whereby clear water is forced to pass from tank 25 through branch pipe 32, valve 35, and inlet pipe 29 into pump 28 and thence through pipe 30 in header 50 and orifices 57^a in paddles 57 so that it is sprayed upon the washed fabrics. The spent water is drained through the open valve 60 into tank 25 to be again forced to circulate through the system by pump 28. 20 25 After the wash is thoroughly rinsed, valve 35 is closed and pump 28 is rendered inoperative. The rinsed clothes can now be placed in the tank containing bluing water or the bluing water can be introduced into 30 the cylinder tank either by filling said tank with bluing water while the valves 60 and 59 are closed or by introducing bluing water in tank 25 and resuming operations same as for rinsing. After the bluing operation, 35 the fabrics can be dried either by subjecting them to the agitating action of the cylinder or by passing them through the wringer.

In order to prevent sediment in tanks 25 and 26 from entering the circulating system, 40 through inlet pipes 32 and 31, tanks 25 and 26 are provided with strainers 70. Removable covers 71 are provided to close open tops of tanks 17 and 18.

By providing a plurality of tanks and 45 connections therefor, the clothes can be washed, rinsed and bluing introduced while the same are in the cylinder, with the least amount of time and labor. The advantages of my washing machine are readily apparent, when the amount of time and labor, required for transferring the wash from the wash tank into the rinsing tub and then into the bluing tank and the wringing operations incidental thereto are taken into consideration. The saving in the wear and tear of 50 55 the fabrics washed by reducing the number of the wringing operations, or, if desired, eliminating the same altogether, in itself is a valuable improvement.

60 A washing machine of my improved construction is of simple and durable construction, can be manufactured at low cost, is highly efficient in operation, and performs its intended functions effectively and without 65 injury to the fabrics.

It will be readily understood that minor changes in the size, form and construction of the various parts of my improved washing machine can be made and substituted for those herein shown and described, without departing from the spirit of my invention, the scope of which is set forth in the appended claims.

What I claim is:

1. A washing machine comprising a housing having a washing compartment, a removable cylinder arranged for operation therein and adapted to receive fabrics, a plurality of hollow paddles disposed in said cylinder, and arranged to agitate said fabrics when said cylinder is actuated, said paddles being provided with discharge openings, a chamber in one end of said cylinder and communicating with said hollow paddles, said cylinder being provided with trunnions, one of which is adapted to engage a driving shaft, journaled in said casing and the other trunnion being hollow and communicating with said chamber on said cylinder, a plurality of tanks located in said housing and adjacent to said washing compartment adapted to contain cleansing fluids, and means for delivering the cleansing fluid from said tanks to said hollow trunnion on said cylinder, whereby the cleansing fluid is discharged into the cylinder through the discharge openings in said paddles.

2. A washing machine comprising a housing having a washing compartment and a plurality of supply tanks positioned below said washing compartment, a cylinder arranged for operation in said washing compartment and adapted to receive fabrics, a plurality of hollow paddles disposed in said cylinder and arranged to lift said fabrics out of the liquid and then permit them to drop back when said cylinder is actuated, said hollow paddles being provided with discharge openings, a chamber in one end of said cylinder and communicating with said hollow paddles, said cylinder being removable journaled in said casing by trunnions, one of which is adapted to be seated in and have rotative engagement with the inner end of a driving shaft journaled in said casing, and the other trunnion being hollow and communicating with said cylinder chamber and adapted to be removably journaled in a bearing in said casing, connections between said hollow trunnion and said tanks, and means interposed in said connections for forcibly discharging the cleansing fluid through the discharge openings in said paddles.

3. A washing machine comprising a casing, a washing compartment in said casing, a cylinder arranged for operation therein and adapted to receive fabrics, a plurality of hollow paddles substantially rectangular in

- cross section and longitudinally disposed in said cylinder and arranged to agitate said fabrics when said cylinder is actuated, and provided with discharge openings, a chamber in one end of said cylinder and communicating with said hollow paddles, said cylinder being provided with trunnions which removably support said cylinder in said casing, one of said trunnions being adapted to 5 engage a driving shaft and the other trunnion being hollow and communicating with said cylinder chamber, a plurality of tanks in said casing and below said washing compartment and adapted to contain cleansing 10 fluids, connections between said hollow trunnion and said tanks whereby the cleansing fluid can be discharged through said discharge openings, and manually controlled means in the bottom of said washing compartment for returning said fluid to its respective tank.
4. In a washing machine, a casing comprising a cylinder compartment and a plurality of tanks located below said cylinder compartment, a revolute perforate cylinder 25 removably journaled in said cylinder compartment, a series of hollow baffles substantially rectangular in cross section and longitudinally disposed in said cylinder and provided in their face walls with perforations, a driving shaft journaled in said casing, trunnions on said cylinder, one of which is adapted to rest in and have a driving connection with said shaft and the opposite 30 trunnion being hollow and adapted to be journaled in a bearing in said casing, a pipe, one end of which is supported in said bearing and adapted to enter said hollow trunnion, one end of said cylinder being provided with a chamber connecting the hollow 35 trunnion with said hollow baffles pipe connections between said pipe and said tanks, and means in said pipe connections arranged to force the liquid from said tanks onto the 40 clothes in said cylinder through the perforated face walls of said baffles.
5. In a washing machine, a casing divided by a horizontal wall into a washing compartment and a plurality of supply tanks below 45 said washing compartment, a cylinder removably journaled in said washing compartment and provided with a series of hollow perforated paddles longitudinally disposed therein and arranged to pick up the articles
- in said cylinder and then drop them back 55 into the liquid during the operation of said cylinder, a driving shaft in said casing, one end of which terminates within said washing compartment, a trunnion non-circular in cross section carried by one end of said cylinder and adapted to be seated in the end of said shaft, a hollow trunnion carried by the opposite end of said cylinder and adapted to be seated in a bearing in said casing, a chamber in said end of the cylinder connecting the hollow trunnion with the hollow paddles, a pipe connected to said tanks and having one end supported in said bearing and adapted to enter said hollow trunnion, and means in said pipe for forcing the liquid 60 from said tanks into said cylinder through said perforated paddles.
6. In a washing machine, a casing having a washing compartment and a plurality of washing liquid compartments disposed below said washing compartment, a revolute cylinder removably journaled in said washing compartment, hollow paddles having flat perforate face walls and longitudinally disposed in said cylinder, a driving shaft 70 journaled in said casing and having one end terminating within said cylinder compartment and provided with a recess which is non-circular in cross section, a trunnion on said cylinder non-circular in cross-section 75 and adapted to be seated in the recessed end of said driving shaft, a hollow trunnion on the opposite end of said cylinder and adapted to be journaled in a bearing within said washing compartment, a pipe having connections with said washing liquid compartments and having one end projecting into said washing compartment through said bearing and adapted to be engaged by said hollow trunnion, a 80 chamber in one end of said cylinder for connecting said hollow paddles with the hollow trunnion, means for forcing the washing liquid from said tanks through said pipe connections and hollow paddles into the cylinder, and means on the recessed end of the 85 driving shaft adapted to lock the non-circular trunnion in position in said recessed end.
- In testimony whereof I hereunto affix my 105 signature this 6th day of October, 1920.

SAMUEL D. CARPENTER.
